ROAD SCRAPER

Eugene L. Schermerhorn, Stanton, Mich.

Application June 26, 1933, Serial No. 677,575

9 Claims. (Cl. 37—143)

This invention relates generally to scraping mechanism and more particularly to a scraping attachment adapted to be positioned underneath a truck chassis frame.

5 One objection to present day structures of this case lies in the fact that they utilize a rock shaft, this rock shaft extending substantially the length of the supporting beam, whereas in my novel construction I eliminate this rock shaft with its appurtenant structure. I am able to accomplish this reduction in structure by means of my novel arrangement of parts and such elimination decreases both the original construction cost and the maintenance cost as 10 well as facilitating initial installation and replacement due to the decrease in weight of the device.

Another advantage of my invention resides in the positioning of the rubber buffer members, 20 these being readily removable and replaceable.

Another advantage resides in the positioning of the return spring for the blade structure, this spring having its greatest pulling effect and its least leverage arm when the blade mechanism is in its lower position and its greatest 25 leverage arm and least pulling effect when the blade is raised, such giving a substantially uniform effect whereby the piston of the hydraulic mechanism is returned to its initial position 30 with a constant velocity.

Yet another advantage resides in the novel blade construction, such being reinforced by the welded angle members which are located immediately adjacent its rear side. Also, the mold 35 board supporting brackets stiffen the blade structure near its ends.

Another advantage resides in the particular location of the trunnions of the cylinder base together with the conduit passing axially 40 through one of these trunnions.

Other advantages will become apparent as the description proceeds.

In the drawings:—

Fig. 1 is a side view of my invention as applied to a truck chassis frame.

Fig. 2 is a plan view of the same.

Fig. 3 is a plan view of one end of the cross beam, part of the hydraulic cylinder and its mounting being shown in section.

50 Fig. 4 is a side view of the structure shown in Fig. 3.

Fig. 5 is a sectional view taken along the line 5—5 of Fig. 4.

Fig. 6 is a front elevation of the mold board 55 supporting bracket.

Fig. 7 is an enlarged fragmentary cross sectional view of the stuffing box connection leading into the hollow trunnion of the cylinder base.

Similar numerals refer to similar parts 60 throughout the several views.

Referring particularly to Figs. 1 and 2, numeral 10 indicates the truck chassis frame having posts 11 depending therefrom by means of the connections 12, these posts being four in 65 number and adjustably receiving the bearing ends 13 of the arc-shaped bars 14. These arc-shaped bars are preferably formed of angular members.

The cross beam 15 extends horizontally below 70 the arc-shaped members 14 and clamping plates 9, see Fig. 2, provide for circumferential movement of the beam 15 about the axis 16, a yoke member 17 maintaining the beam from lateral movement. The beam is bent downwardly at 75 its center portion to provide clearance thereabove.

A supply pipe 19, adapted to receive pressure fluid from the flexible conduit 18, lies alongside 80 of the beam 15. See Figs. 1, 2, 3 and 4.

As shown in Fig. 2, hydraulic operating mechanism and spring retracting mechanism is located at each end of the beam 15, and as such structures are identical, only one will be described.

Journal members 20, see Figs. 1 and 4, are 85 located to the underside of the beam 15 in spaced relationship to each other and a short shaft 21 extends therethrough, being held from endwise movement by the cotter pins 22. The mold board supporting bracket, see Fig. 6, has arms 90 23, terminating in bearing members 24 extending upwardly therefrom, these bearing members being pivotally mounted upon the shaft 21. Flanges 25 extend laterally from the mold board supporting bracket and receive the bolts 26 95 28, whereby the same is rigidly attached to the angle member 30 and the blade 40. A lug 27, see Figs. 4, 5 and 6, extends from one of the flanges 25 and receives one end of the coiled spring 28. The upper end of this coiled spring 100 28 is adjustably fastened as at 29 to the arm 31, this arm being fastened as at 32 to the end of the beam.

The mold board supporting bracket, see Figs. 5 and 6, has a recess 33 adapted to receive the 105 head of the bolt 34, the shank of the bolt 34 detachably fitting into the slot 35.

An actuating member 36, having an upwardly extending lever arm 37, has a pivotal arm 38 which extends laterally and upwardly as shown 110

in Fig. 1 and which is pivotally mounted as at 39 on the central portion of the shaft 21. See Fig. 4.

The lower part of the actuating member 36 5 is rounded as shown in Fig. 4 and has an opening 41 extending therethrough, this opening receiving the bolt member 34. A buffer cylindrical member 42, preferably formed with rubber, extends around the bolt 34 and is received between 10 the actuating member 36 and the mold board supporting bracket.

The angle member 30, previously referred to, is welded to a second angular member 43, see Figs. 1 and 4, and bolts 44, together with the 15 bolts 26, previously referred to, securely fasten these angle members to the scraper blade 40.

From the structure so far described, it will be seen that the angle members 30 and 43, are of relatively great strength and that these members, together with the blade 40, form a cross beam which is of very sturdy construction and this construction entirely eliminates the rock shaft which is usually present in devices of this character. The mold board supporting brackets 20 are freely pivoted upon the shafts 21 and likewise the actuating members 36 are also freely pivoted upon these same shafts. The buffer members 42 are located between the actuating members and the depending bracket members 30 and these buffer members transmit the downward force from the lever arm 37 to the blade member 40, the buffer members yielding under excessive pressure or under shocks and impacts 25 to damper out any vibrations due to the blade meeting with an obstruction or the like.

The lever arm 37 is connected to and actuated by the piston 45, such piston having a yoke 46 at its outer end, this yoke being connected at 47 to the upper end of the lever arm 37. 40 See Figs. 1 and 3. A cylinder 48 threaded into the base 49 receives the piston 45. The base 49 has trunnions 50, these trunnions 50 being mounted in the extensions 51 and 52 of the bracket members 53 and 54, respectively. The 45 bracket members 53 and 54 are respectively provided with a groove 55 and a tongue 56 whereby proper alignment may be had between the bearings on the extension arms 51 and 52, respectively. Thus the trunnions 50 of the cylinder 50 base 49 freely rotate about their axes.

The trunnion 50, see Fig. 3, has a conduit 57 leading axially therefrom, the pressure conduit 19, previously referred to, being connected thereto by means of the stuffing box 58. As 55 is shown in Fig. 7, a metal washer 59 located between the backing 60 and the outturned flange 61 of the conduit 19, permits turning movement between the trunnion 50 and the conduit 19.

A pipe 63 leading from and connected to the 60 conduit 57 by means of the stuffing box 64, enters the end of the cylinder 48 at 65 and thus the pressure fluid may flow into the cylinder 48 therethrough.

The operation will be apparent. The beam 65 15 is adjusted to the desired position and pressure fluid is had through the conduits 18 and 19, the fluid flowing through the stuffing box 58, the passageway 57, the second stuffing box 64, the pipe 63 and entering the cylinder 48 whereupon the fluid pushes the piston 45 outwardly. This outward movement of the piston 45 moves the arm 37 and the actuating member 36 thus causing movement about the shaft 21. 70 The buffer member 42 transmits this pressure 75 to the mold board supporting bracket, which is

freely pivoted upon the shaft 21, and thus the blade and its reinforcing structure is forced downwardly to operative position as shown in Fig. 1.

Whenever the pressure is released from the operating fluid, the coiled springs 28 contact and raise the blade from its operative position, and exert pressure in a reverse manner so that the pistons 45 traveling into the cylinders 48 force the hydraulic pressure fluid back through the conduits 19 and 18. It is to be noted that the springs 28 act upon the scraping blade structure and hence through the buffer members 42, thus giving a damped and even pressure upon the pistons 45 whereby shocks will be 80 85 90 eliminated.

Also, the springs 28 are located at an angle to the vertical whereby the effective lever arms, as shown in Fig. 1, are at a minimum when the springs are fully extended and as the blade is lifted the length of these lever arms increases in order to compensate for the diminished pulling effect of the springs 28. Thus a substantially constant pulling effect is had through the yielding 95 100 105 buffer means 42.

As shown in Fig. 3, a tongue 56 extends into the recess 55 of the adjacent bracket member and these snugly engage in order to properly mount the trunnions 50. Also, this construction permits the insertion of an extra bolt passing 105 downwardly therethrough to mount the same upon the beam 15.

As the scraper blade is raised from the position shown in Fig. 1, the lever arm 37 moves rearwardly and also upwardly and thus the 110 trunnions 50 turn slightly in the extension arms 51 and 52 and this is taken care of by the stuffing box construction shown in Fig. 7, such permitting circumferential movement between the trunnion 50 and the conduit 19.

Without limiting myself to the particular embodiments of my invention illustrated and explained above, and desiring to protect my invention in the broadest manner legally possible, what I claim is:—

1. In a road scraping mechanism of the class described, the combination of, a truck chassis frame having four spaced apart posts mounted thereon, arc-shaped bars horizontally mounted upon said posts for vertical movement thereon, a horizontal beam adjustably mounted on said arc-shaped bars, hydraulic means located on said beam, a scraping blade pivotally mounted on said beam, means interconnecting the hydraulic means and the beam whereby introduction of 125 pressure fluid in the hydraulic means will cause actuation thereof and move the blade with respect to the said beam, said hydraulic means including a cylinder and a cylinder base with trunnions pivotally mounted on the said beam, 130 one of said trunnions having a passageway axially therein, means for supplying fluid to said passageway and means leading from said passageway to the interior of the cylinder for the purpose described.

2. In a road scraper having a cross beam, two spaced apart mold board supporting brackets pivotally attached thereto, two actuating members pivoted adjacent said brackets, buffer means between said actuating members and said 145 brackets, a scraping blade fastened to said mold board supporting brackets and means for moving said actuating members.

3. In a device of the class described, a beam, means for mounting said beam, journal members 150.

- located on said beam in spaced relation to each other, mold board supporting brackets pivoted for free operation upon said journals, blade mechanism including two angles welded together and a blade bolted to said angles attached to said mold board supporting brackets, and buffer means for exerting pressure upon said blade mechanism for the purpose described. 5 each of said shafts, blade mechanism mounted upon said brackets, an actuating member pivoted upon each of said shafts, and rubber means located between said actuating members and the said mold board supporting brackets. 80
4. A combination of elements as set forth in 10 claim 3 in which actuating members operate said buffers, said actuating members being pivoted upon the said journal for free pivotal movement thereon. 85
5. In a device of the type described having a 15 beam with a scraping blade pivotally mounted thereon, the combination of, buffer means located rearwardly of said blade, pivoted means having surfaces abutting against said buffer means, and hydraulic means including a cylinder, a piston sliding in said cylinder, means connecting said piston to the said pivoted means, a cylinder base having trunnions laterally extending therefrom, extensions adapted to receive said trunnions, and guiding means between said 20 25 extensions to properly align the same whereby the cylindrical base trunnions will freely turn about their axes. 100
6. In combination, a cross beam, a pair of spaced journal members located at each end thereof, shafts extending through each of said 30 pairs of journal members, a mold board supporting bracket pivoted upon and depending from 105
- each of said shafts, blade mechanism mounted upon said brackets, an actuating member pivoted upon each of said shafts, and rubber means located between said actuating members and the said mold board supporting brackets. 80
7. A combination of elements as set forth in claim 6 in which said rubber means has a hole therethrough, bolt means extending through the said hole and also through the said actuating member, the mold board supporting brackets each having a slot therein adapted to detachably receive the head of said bolt therein. 90
8. A combination of elements as set forth in claim 6 in which said blade construction includes two angles rigidly attached to its rear face for the purpose described. 95
9. In a scraper structure, the combination of, an adjustable supporting beam, journal means mounted below each end of the said adjustable supporting beam, shafts positioned in said journal means, moldboard supporting brackets pivotally mounted one on each of the said shafts, actuating members also mounted one on each of said shafts, each of said actuating members having an arm extending upwardly therefrom, scraping means rigidly attached to said moldboard supporting brackets, yieldable means located between said moldboard supporting brackets and the actuating members and means for moving the said arms of the said actuating members for the purpose described. 100
